(57) **CLAIM**

The ornamental design for a utility vehicle top and rail assembly, as shown and described.

DESCRIPTION

FIG. 1—is a right side elevational view of a utility vehicle top and rail assembly showing my new design;

FIG. 2—is a rear perspective view thereof;

FIG. 3—is a right rear perspective thereof in an alternate position of use with the tonneau cover and rear window removed;

FIG. 4—is a rear perspective view thereof; and,

FIG. 5—is a front perspective view thereof.

The broken lines in the drawings indicate environmental structure and form no part of the claimed design.
